UNITED STATES PATENT OFFICE.

JOHN E. HEIKKILA, OF SYRACUSE, NEW YORK.

AUTOMATIC WINDOW-LATCH.

1,233,055.

Specification of Letters Patent. Patented July 10, 1917.

Application filed November 2, 1916. Serial No. 129,155.

To all whom it may concern:

Be it known that I, JOHN E. HEIKKILA, a citizen of the United States, and resident of Syracuse, in the county of Onondaga and State of New York, have invented certain new and useful Improvements in Automatic Window-Latches, of which the following is a specification.

The present invention relates to window latches and has for its primary object the provision of a novel and simple form of automatic window latch adapted for installation on the meeting rails of sliding sashes.

Another object of my invention is to provide a window latch of the class described which upon moving the sashes of a window to closed position automatically locks the sashes in such position.

A further object of my invention is to provide a window latch of the class described which will not in any way interfere with the manipulation of the sashes when open and one which is entirely automatic in so far as the locking feature is concerned.

A still further object of my invention is to provide a latch of the class described which is strong and durable, may be cheaply manufactured and sold, does no require any skill in installing the same, and is effective in operation.

Other objects and advantages to be derived from the use of my improved automatic window latch will appear from the following detailed description and the claims, taken with an inspection of the accompanying drawing, in which:

Figure 1 is a fragmental sectional view of a pair of window sashes showing my improved latch applied thereto in open position;

Fig. 2 is a similar view showing the latch in closed position; and

Fig. 3 is an enlarged detail perspective view of the latch arm.

Referring more particularly to the drawing, wherein similar characters of reference designate like and corresponding parts throughout the various views, 10 and 11 designate the upper and lower sashes of a window, the same having the usual beveled meeting rails 12 and 13, respectively.

The latching device of my invention includes an abutment member designated A in its entirety and mounted on the upper surface of the rail 13. A supporting block B is mounted on the rail 12 and carries a latch arm a described in detail hereinafter.

Referring specifically to the abutment member A, the same consists of a body formed with a base portion 15 through which a plurality of screws 16 or the like are engaged for retaining the member A on said rail 13. The upper end of the member A is provided with a pair of projections 17 and 18, the projection 18 is pyramidal in appearance having converging curved surfaces 19.

The member A is provided with a recess 20 and a pair of aligned transverse openings 21 in which the sliding bolt 22 is mounted, said sliding bolt projecting from the inner surface of the member A under the action of a coil spring 23. The outer free end of the sliding bolt 23 is provided with a knob or handle 24 for withdrawing the same.

The latch arm a is preferably curved in general contour, the same being provided with an opening 25 through which a bearing pin 26 is engaged, said latch arm a being mounted between the standards 27 formed on the member B. The inner edge of the member A is recessed as at 28 to conform to the shape of the projection 18, and the free end of the member A is beveled as at 29 to conform to the inner edge of the projection 17 so that said arm a will snugly engage the member A when in locked position.

The latch arm a is provided with a recess 30 having a straight bottom wall 31 and a diagonal top wall 32. A shoulder 33 is formed on the member B between the arms 27 to limit the movement of the latch arm a and prevent the same from contacting with the window pane.

When closing the window, the sashes will be moved into engagement as shown in Fig. 1, the arm a being in the inoperative or unlatched position and the sliding bolt projecting from the member A. When the bolt strikes the recess 30 the arm a will be caused to swing into engagement with the member A as shown in Fig. 2. While the wall 32 of the recess 30 is inclined, the angle of inclination is not sufficient to permit reopening of the arm by raising the sash, the free end of the bolt 22 engaging the wall 32 thereby preventing raising of the lower sash or lowering of the upper sash. Of course, the arm a is at this time engaged with the member A, and in view of the curved surfaces 19 of the projection 18 engaging snugly in the recess 28 the strain is removed from the bolt and distributed throughout the arm a and said projection. It will be readily apparent that my improved latch is automatic in operation.

in so far as the locking feature is concerned. Of course, when it is desired to open the window it is necessary to withdraw the bolt 22 from engagement with the recess 30 thus 5 permitting rotation of the arm *a* and disengagement of the same from the member A thereby unlatching the sashes. The device of my invention may be readily applied to any window having sliding sashes by means 10 of a hammer and screw driver.

From the above description taken in connection with the accompanying drawing, it is thought that a clear and comprehensive understanding of the construction, operation 15 and advantages of my invention may be had, and while I have shown and described the device as embodying a specific structure, I desire that it be understood that such changes may be made in said structure as 20 do not depart from the spirit and scope of the invention as claimed.

Having thus fully described my invention, what I claim as new and desire to secure by Letters Patent, is:

25 1. In a device of the character described the combination with the meeting rails of window sashes, of an abutment comprising a body portion, a base formed on the body portion adapted to be secured to one of the 30 meeting rails, a pair of projections formed on the upper part of the body portion, the surface of one of the projections being curved, the abutment being provided with a recessed portion, said abutment being provided with 35 alined openings on opposite sides of the recess, a sliding bolt mounted in the openings, a coil spring mounted on the bolt within said recess, a supporting member rigidly secured to the other meeting rail, and a latch arm 40 pivotally mounted on said supporting member, having a recessed portion adapted to normally engage the bolt, the latch arm being provided with a recessed portion adapted to be engaged by the projections for a purpose 45 specified.

50 2. In a device of the character described the combination with the meeting rails of window sashes, of an abutment comprising a body portion, a base formed on the body portion adapted to be secured to one of the meeting rails, a pair of projections formed on the upper part of the body portion, the surface of one of the projections being curved, the abutment being provided with a recessed portion, said abutment being provided with 55 alined openings on opposite sides of the recess, a sliding bolt mounted in the openings, a coil spring mounted on the bolt within said recess, a supporting member rigidly secured to the other meeting rail, a pair of standards 60 mounted on the supporting member, having a transverse opening in one end thereof,

a pin mounted in the openings of the supporting member and the latch arm to pivotally engage the same, the latch arm having a recessed portion adapted to be normally engaged by the bolt, the latch arm being provided with a recessed portion adapted to be engaged by the projections, and the free ends 70 of the latch arm member being beveled for a purpose specified.

3. In a device of the character described the combination with the meeting rails of a window sash, of an abutment comprising a body portion, a base formed on the body portion adapted to be secured to one of the meeting rails, a pair of projections formed on the upper part of the body portion, the surface of one of the projections being curved, the abutment being provided with a recessed portion, said abutment also being provided with alined openings on opposite sides of the recess, a sliding bolt mounted in the 80 openings, a coil spring mounted on the bolt within said recess, a supporting member rigidly secured to the other meeting rail, and a latch arm pivotally mounted on said supporting member having a recessed portion, said recessed portion having a straight bottom wall adapted to be normally engaged by the bolt, said supporting member having a shoulder formed thereon, the latch arm being adapted to engage said shoulder, said latch arm member being recessed to conform to the 95 shape of one of the projections to engage the same, and the free ends of the latch arm being beveled to conform to the inner edge of the other projection for a purpose specified.

4. In a device of the character described 100 the combination with the meeting rails of window sashes, of an abutment comprising a body portion, a base formed on the body portion adapted to be secured to one of the meeting rails, a pair of projections formed 105 on the upper part of the body, the surface of one of the projections being curved, the abutment being provided with a recessed portion, said abutment being provided with alined openings on opposite sides of the recess, a sliding bolt mounted in the openings, a coil 110 spring mounted on the bolt within said recess, a supporting member rigidly secured to the other meeting rail, a pair of standards mounted on the supporting member, a shoulder formed between the said standards, a latch arm pivotally secured to the standards the movement of which being limited by said shoulder, said latch arm having a recessed portion adjacent one end adapted to be engaged by said bolt, and a portion of the latch arm being of a contour supplemental to that 115 of the abutment for a purpose specified.

In testimony whereof, I affix my signature hereto.

JOHN E. HEIKKILA.
